GREENHOUSE CONSTRUCTION

Stephen H. Hart, Irvington, N. Y., assignor to
 Lord & Burnham Company, Irvington, N. Y., a
 corporation of New York

Application July 11, 1929, Serial No. 377,389
 Renewed March 9, 1933

6 Claims. (Cl. 108—16)

This invention relates to greenhouse construction and relates more particularly to improved features of construction so that the drip water of condensation may be readily disposed of. This

5 invention also comprehends improved features of construction relating to the roof bars, their supporting members and the framing of the ends. This invention further relates to improved features of construction enabling extensions and additions to the width of the greenhouse to be 10 readily made without requiring the reconstruction or tearing down of side walls or partitions already in place.

In the construction of additional sections or 15 units in order to increase the width of greenhouses already constructed, particularly where a supplemental drip gutter is below the main gutter, it has usually been necessary to tear down and reconstruct the side to which the extension is 20 to be added in order to dispose of the drip water of condensation. This is particularly true where an intermediate, main and supplemental drip gutter is employed as a common gutter between the two sections.

25 One of the objects of this invention is to provide an improved construction for greenhouses, particularly in the type employing a main gutter having a bottom comprising oppositely inclined portions, with a condensation drip gutter therebelow, the construction being such that in the event that it is desired to widen the greenhouse by adding an additional section to the width thereof, it will not be necessary to tear down and reconstruct the glass frame constituting the side of the 30 original structure, but will permit the water of condensation from the roof bars on one side of the added section to be carried to the drip gutter of the original section merely by the removal of a longitudinally extending closing or sealing 35 finishing strip which closes or seals a space which has been left between the bottom of the original main gutter, and the top of the glazing fascia on the side of the original section of the greenhouse. This is an important feature of construction in 40 that it effects a considerable economy and saving in the labor and materials where any additional section is to be added, but yet in the original construction of the first section, the labor and material costs is not substantially increased.

45 A further object of this invention is to provide an improved combination glazing strip and condensation gutter formed as a hollow and tubular member adapted to be mounted on the side of a main gutter, or on a sill, said member serving to 50 perform the double function of a glass stop, and also to serve as a condensation gutter adapted to receive the drip water of condensation directly from the ends of the roof bars and also from the glass between the bars and to convey the water 55 of condensation thus collected from within the

greenhouse, through the hollow portion of the tubular member to be discharged directly in the main gutter and to a point outside of the greenhouse.

65 A further object is to provide a combined glass stop and a drip gutter formed preferably as a hollow member formed of sheet copper or the like, the combined member being mounted on the upper edge of the gutter side and having a greater portion of the area of the combined member subject to, and exposed to the temperature within in the greenhouse whereby, in cold weather, the heat from within the greenhouse, may be conducted to those portions of the sheet copper gutter exposed to the outside temperature in 70 order to minimize the possibilities of formation of ice and the clogging of the drain apertures for the water of condensation.

75 A further object of this invention is to provide an improved metal channel bar construction for 80 seating and strengthening the usual wooden roof bar having the condensation groove therein, the improved metal bar being in such form as will present a flat surface on the bottom thereof so as to readily permit the wooden roof bar to be 85 uniformly wedged and seated in the metal bar by a screw or the like passing through the base of the metal bar, into the wooden roof bar and to further enable the metal channel bar to be seated and secured on the flat surface presented 90 by a rafter or purlin without requiring the introduction of another yielding medium or member which according to prior practice, is usually interposed between the metal bar and the flat surface of the rafter or purlin in order to obtain a proper seating of the metal bar which supports and 95 carries the wooden roof bars.

100 A further object is to provide a metal bar adapted to receive the wooden roof bar having drip grooves therein, the construction of said bar being such as to minimize the number of fastenings and fixtures required for maintaining the roof bar and the metal bar in cooperative relation and also to minimize the amount of drilling and tapping required in the metal bars.

105 A further object is to provide an improved clasp or fitting for connecting the roof rafter having a metal roof bar with a wooden roof bar therein, and extending on the top and longitudinally of the metal roof rafter in cooperative relation to an angle bar having its ends abutting the roof rafter normal thereto, the said fixture comprising a unitary member which is so disposed as to securely clamp the three members, including the roof rafter, the roof bar and the purlin 115 in fixed relation.

120 A further object is to provide an improved metal channel for a wooden roof bar, said channel presenting a flat portion whereby when used in combination with the combined glazing strip

and tubular sheet metal drip gutter, the end of the wooden roof bar may terminate at the edge of the roof gutter so as to permit the water of condensation from the groove in the wooden roof bar to discharge directly into the drip gutter, independent of other fixtures, but yet permit the metal roof bar supporting the wooden roof bar, to be extended to a suitable point where the flat surface of the metal roof bar may be fixed to the flat surface of a support, and there secured by a bolt or the like without the necessity of using independent special brackets and fixtures.

In the accompanying drawings, certain selective embodiments of the invention are shown, for illustrative purposes only, in order to show the various features of construction which are hereinafter more fully described, and set forth in the claims. It is understood, however, that various changes and modifications may be made by the person skilled in the art, without departing from the spirit and scope of the invention as defined in the appended claims. In the drawings:

Figure 1 is a broken fragmentary perspective, partly in section showing the main gutter with a tubular sheet metal member and glazing strip and drip gutter, with the roof bars on one side of the main gutter showing the detachable sealing strip closing the space between the upper frame member on the side, and the gutter.

Figure 2 is a fragmentary perspective, partly in section, showing the application of the hollow tubular sheet metal combination glass stop and drip gutter employed in connection with the sill at the top of the side or gable wall and also showing the end of the roof bar with the condensation drip groove discharging directly into the drip gutter, and the metal roof bar presenting a flat surface which is secured to the sill through an angle iron bracket or clip presenting a flat surface.

Figure 3 is a fragmentary perspective partly in section, showing the side wall and sill of a greenhouse with a modified form of the tubular sheet metal combination glass stop and drip gutter.

Figure 4 is a fragmentary section taken on the line 4—4 looking in the direction of the arrows in Fig. 1, showing the relative arrangement of the roof rafter, roof bars, and the glass.

Figure 5 is a section taken on the line 5—5 looking in the direction of the arrows in Fig. 4.

Figure 5a is a section of wood roof bar showing a modified form of combined roof rafter and roof channel.

Figure 6 shows diagrammatically a section through a greenhouse showing the drip gutter and detachable sealing strip on an enlarged scale for purposes of clearness, in order to illustrate, when considered in connection with Figs. 8, 7 and 9, that additional sections might be added either side of the single section shown in Fig. 6 without requiring the removal or reconstruction of either of the sides of the single section.

Figure 7 is an enlarged section taken on the line 7—7 of Fig. 6 showing the relative position of the parts including the main gutter with a drip gutter therebelow having the roof bars on one side of the gutter and one side of the greenhouse section at the other side of the gutter, and having the improved detachable sealing strip feature which facilitates the construction of an additional house paralleling one or more existing units.

Figure 8 is a diagrammatic view showing certain features of construction, such as the gutter and the related parts on an enlarged scale for purposes of clearness, in order to show diagram-

matically the relative position of the parts after the additional side section has been added.

Figure 9 is an enlarged section taken on the line 9—9 of Fig. 8.

Figure 10 is a fragmentary sectional view on line 10—10 of Fig. 7 showing the top frame member of the side of the greenhouse and the gutter bottom thereabove in order to show the space between the under side of the gutter and the top frame member of the side, and showing also the bracket in said opening for positioning the side of the greenhouse relative to the gutter.

Figure 11 is a side elevation of the core bar and the metal roof bar supporting the same, showing the purlin and the glass in section.

Figure 12 is a side elevation of Fig. 11 showing the wooden roof bar and the metal channel and glass in section.

Figure 13 is a view showing the roof bar, the metal roof bar channel and the roof rafter in section, and the purlin in elevation, an improved clamping member also being shown in elevation, for holding the three members in proper relative position.

Figure 14 is a side elevation of Fig. 13 showing the purlin and the glass in section.

Figures 15 and 16 are sections showing a roof bar with condensation grooves therein and a modified form of roof bar and channel.

In Fig. 1 a gutter 1 is shown as comprising a bottom having oppositely sloping portions 2—3 which intersect and meet at 4 in the middle of the gutter. Preferably, a concentrating ridge 5 is provided on the bottom of the gutter in order to facilitate and insure the delivery or dropping of the water of condensation to a supplemental drip gutter 6 which is mounted below. The gutter provided with upstanding sides 7—8. Shoulders 9—10 are preferably provided on the upper edge of the sides 7—8 in order to facilitate the mounting and support of a hollow tubular sheet metal member which serves the double function and purpose of a glazing strip or glass stop and a drip gutter arranged to receive the water of condensation discharged directly from the drip groove in the roof bars, and also from the glass between the roof bars.

The hollow sheet metal member performing the double function of a glazing strip and supplemental drip gutter, is preferably formed of sheet copper which is a relatively good heat conductor. The advantage of this material being that the heat from within the greenhouse may be conducted to the portion of the tubular member exposed to the outer atmosphere, so that in cold weather, the probability of the drain apertures becoming clogged with ice is minimized. The construction of the member forming the combined glazing strip and drip gutter may assume various forms, but as shown, comprises a body portion generally rectangular in form as indicated by the rectangular section 11 the bottom or base 12 being seated on the upper edge 13 of the gutter side. A downwardly extending leg portion 14 is formed at one side of the tubular member, which leg portion is seated in the shoulder 9 of the gutter side 7. On the top member of the tubular member a plurality of upstanding ridges 15—16 extend longitudinally of the member, the ridge 15 being spaced inwardly from the inner vertical side 17 a sufficient distance to form a seat 18 for the glass 19, and serves in connection with the ridge 15 as a glass stop and glazing strip.

The ridge 15 also forms one side of the drip gutter designated generally by 20. The other

upright side of the drip gutter being formed by the ridge 16 which is formed as a continuation of the outer side 21 of the tubular member designated generally as 11. Instead of providing independent specially formed outlets or downspouts to carry away the water of condensation from the drip gutter, the drip water of condensation is carried from the drip gutter 20 through drain apertures 22 which are formed at spaced intervals 5 through the interior of the tubular members directly to the main gutter through other drain apertures 23 formed near the bottom of the side 17 of the drip gutter; the drain apertures 22-23 are in alignment or so disposed as to permit a 10 straight instrument to be passed therethrough in order to clean such opening from obstructions in the event that they become clogged.

As shown, a part of the sheet metal tubular member extends beyond the outer vertical side of the gutter so that a relatively large surface is exposed to the heat or temperature within the 15 greenhouse.

The main gutter is shown supported on the bracket 24 mounted on a post 25, the member 24 being provided with arms 26 extending outwardly and upwardly in order to receive the gutter bottom; one of the arms is shown broken away for 20 purposes of clearness. If for any reason it is desired to carry the drip water of condensation to the bottom side of the gutter, a supplemental drip gutter 6 may be supported in the bracket 24 below the main gutter.

One contingency in which it might be desirable to use the supplemental drip gutter 6 in addition to the tubular sheet metal gutter mounted on the top edge of the gutter side, would be where it is desired to add an additional section at the side of the section first constructed and to do this without the necessity of another tubular 30 sheet metal drip gutter mounted on the top edge of the other side of the main gutter. Where the sheet metal tubular member is employed which performs the double function of a glazing strip and drip gutter, a gutter having either a flat bottom, or a V bottom may be employed. Where 40 a supplemental drip gutter is disposed below the main gutter, the bottom of such main gutter is preferably formed of oppositely inclined portions.

Where a construction is employed as shown in Fig. 1, having a gutter with a V shaped bottom with a supplemental drip gutter therebelow, and a tubular sheet metal combination glazing strip and drip gutter mounted on the upper edge of one of the upright sides of the gutter, it readily adapts the gutter for use as a middle gutter to 50 carry away the water from two adjacent greenhouse sections having different constructions, having reference more particularly to the framing of the roof bar ends adjacent the gutter sides. For example, the roof bars in one section could 55 be of the curved type as shown in Fig. 1, and the roof bars of the adjacent section on the other side of the middle gutter might be of the straight roof bar construction such as that illustrated in Fig. 7, hereinafter more fully described. In one instance, the drip water of condensation would be carried to the main gutter, and in the other instance, the drip water of condensation would 60 be carried to the supplemental drip gutter below the main gutter.

In the formation of the gutter in the form of the tubular member serving the double function of a glass stop and condensation drip gutter, it may be formed from a one piece tubular member 70 having a continuous periphery, which may be

subjected to the necessary series of manipulations in order to form the substantially rectangular body portion with the depending leg from the bottom, and the upstanding ridges at the top; if desired, the tubular member may be formed of a plurality of longitudinally extending pieces of the sheet metal. If two pieces of sheet metal are used, preferably, one piece is employed to form the two sides and bottom of the drip gutter, and the second sheet if formed by one continuous piece of the proper contour and having its ends suitably secured to the ends of the first piece, as shown in section in Fig. 1.

In common practice heretofore employed in placing the ends of the roof bar, in such manner as to secure the proper strength, and also the proper disposition of the water of condensation, it has been usual to provide a metal bracket or fixture for supporting the ends of the roof bars in proper relation relative to the gutter.

As shown in Fig. 1, the greenhouse illustrated is of a type in which the lower end of the roof bars are curved. Fig. 4 is a fragment of a side elevation showing the roof rafter, the wooden roof bar and the metal roof bar channel for seating and strengthening the wood core bar. Fig. 5 is a section on line 5-5 of Fig. 4 which shows more clearly the wooden roof bar 27 having drip grooves 28 therein. As shown, the roof bar metal channel designated generally as 29, is provided with a flat 100 base 30 having the upwardly and outwardly extending sides 31, which receive and seat the lower portion of the wooden roof bar which is correspondingly formed. In greenhouse construction, a certain number of the roof bars extending from 110 the ridge to the eave comprise the wooden roof bar and the channel roof bar; in order to give additional strength to the structure at certain intervals, roof rafters may be used extending below and longitudinally of the roof bars.

One of the difficulties heretofore encountered is to get a suitable seating and connection between the metal roof bar channel and the roof rafter. Heretofore it has usually been necessary to interpose an intermediate yielding strip between the roof rafter and the roof bar channel in order to maintain a proper seating and connection therebetween, and also to employ a number of additional clamps and fixtures for holding these parts in proper relation. In accordance 120 with the present construction, the intermediate yielding member has been entirely eliminated and by employing a metal roof bar channel having a flat base or bottom therefor, it is readily adapted for mounting upon a roof rafter presenting a flat 125 surface extending longitudinally of the bar and is likewise equally well adapted for mounting upon purlins in the form of angle irons presenting flat surfaces extending transversely of and below the metal roof bar, in a manner more clearly shown 130 in Figs. 11 and 12. In these figures an angle iron purlin comprising the flanges 33 and 34 normal to each other, extend transversely of and below the roof channel bar 29, the flat base 30 being seated on the horizontal leg 34 of the purlin; the wooden 135 core bar 27, and the metal roof bar channel 29, are held in proper fixed relation by the use of a screw 35 or the like. The metal roof bar channel 29 and the purlin are preferably secured together by a machine screw 35 or the like. One distinct 140 advantage in having the bevelled roof bar adapted to seat in the correspondingly shaped sides of the metal channel, is that when the securing means 35 is tightened, the effect is to exert a powerful force to draw the wooden roof bar and the metal 145

channel bar into proper seating relation by a wedging action, the effect of which is to cause the wooden roof bar to be evenly and uniformly seated on each side of the channel. One of the objections to the angle iron construction heretofore employed in the prior art, is that no flat surface is available on the bottom of the metal roof bar channel; this made it necessary to drill counter sunk additional holes in each of the upwardly and outwardly extending sides, the result of which was that it was impossible to get an even and uniform seating of the wood roof bar acting uniformly on both sides of the metal roof bar channel; the prior art construction frequently resulted in a close fitting and seating on one side and leaving a space on the other side of the roof bar.

As shown in Fig. 5, there is preferably employed a roof rafter having a vertical web 32 and a web portion 36, normal thereto, which web or leg portion is flat and is substantially the width of the flat base of the roof bar channel. By having the main supporting web 32 of the roof rafter offset from the center of the roof bar, it is possible to utilize a common securing member 35 passing through the web 36 of the roof rafter, and the base 30 of the roof bar channel and into the wooden roof bar 27. This securing means serves to forcibly draw the three members into proper relation. If additional clamping means is desired between the roof rafter and the roof channel, the clamping bracket 37, 38 such as that shown in Fig. 13 may be employed.

As shown in Fig. 13, a roof rafter having merely the vertical web 32 is shown, on the upper flat edge of which is seated the roof bar channel. The roof rafter 32 and the channel 29 are held in proper fixed relation by means of the clamping members 37 and 38 arranged one on each side of the roof rafter and channel, these clamping members 37 and 38 being so formed as to present a hooked portion 39 at the upper portion thereof which engages the upper edge of the sides 31 of the roof bar channel so that as the clamping bolt 40 is tightened, the roof rafter and the roof bar are rigidly held in fixed relation. As shown in Figs. 13 and 14, one of the clamping members 38 is provided with a flange 41 which is normal to the body of the clamp 38 which engages the roof rafter. By means of the clamp 41, and a clamping nut and bolt 42, the purlin 33 may also be supported and held in proper fixed relation relative to the roof rafter 32 and the roof channel 29. A clamping fixture such as that shown in Figs. 13 and 14, holds in proper relative relation the three members including the roof rafter, the roof bar channel, and the purlin angle iron at that point at which the purlin abuts against the roof bars. Heretofore, in the art, a plurality of independent clamping fixtures have been employed. If desired, an additional clamping or bracket 43 may be employed for strengthening the connection between the vertical web of the purlin 33, and the roof rafter 32.

Fig. 16 shows a modified form of construction in which the roof rafter and the metal roof channel bar are formed as a unitary member which performs the two functions of a roof rafter and metal roof bar channel. One distinct advantage of such a construction is that the problem of effecting a connection between the roof rafter and the roof bar channel is entirely eliminated, making unnecessary the employment of any clamping means whatever. By having the vertical web 44 serving as the roof rafter, offset from the

center of the roof bar, it still permits the fastening means 45 such as a screw or the like to pass through the roof bar channel into the wooden roof bar so as to draw the latter into seated relation by a wedging action in the outwardly or upwardly extending sides 46 and 47.

Fig. 15 shows a modified form of roof rafter in which the roof bar channel is eliminated. The flat flange formed integral with the roof rafter web 44 forms a flat seat to receive the wooden roof bar. The vertical web 44 is offset from the roof bar center to permit the securing means as a screw 45, to be used to hold the roof bar and roof rafter in proper position.

Fig. 5a shows a modified form of a combination unitary roof rafter and roof bar channel. A vertical web portion 48 is shown, which serves as a roof rafter which gives strength and rigidity to the structure. The flat portion 49 is normal to the vertical web 48 and serves as a seat for receiving the base of the wood core bar 27, and the upwardly and outwardly extending sides 50 function in the same manner as the sides 31 of the metal roof bar channel shown in Fig. 5. The usual screw 35, or the like, may be used, to pass through the flat portion 49 and into the wooden roof bar, for drawing by a wedging action between the sides 50 and base 49 into close seating relation with the combined integral and unitary roof rafter and metal roof bar channel. If desired, such a unitary and integral combination member may be formed from an angle bar member in which the horizontal flange or web is thinner than the vertical web 48 which serves as the main strengthening roof rafter. If the unitary member is formed from an angle iron in which the horizontal web is thinner than, or, if desired of equal thickness to the vertical web 48, the side members 50, may be readily formed by bending the end portion of the horizontal web, from a position indicated by the dotted line position, 51 through an angle to the position designated by the sides 50.

Figures 1 and 2 show more clearly the construction and relative arrangement of the parts at the end of the roof bars, and illustrates the manner in which the end of the wood core bar 27 terminates above the condensation drip gutter 20 formed on the upper surface of the hollow tubular sheet metal member 11, so that the water of condensation is discharged directly from the condensation drip groove 23 in the roof bar into the metal condensation drip gutter designated generally as 20. The metal roof bar channel designated generally at 29 continues downwardly beyond the hollow sheet metal drip gutter, to a suitable point of support to which the flat base 30 of the channel member may be suitably connected and secured by a bolt or other suitable means to another flat surface such as a web 52, of an angle bracket mounted on the sill 53, as shown in Fig. 2. This is a very desirable feature of construction, in that the framing of the roof bar ends, is obtained in a simple and effective manner, without the employment of special fittings and brackets, and when employed in combination with the sheet metal drip gutter, the water of condensation is readily disposed of.

As shown in Figs. 2 and 3, the sill 53 is disposed and seated on a usual side wall 54 of a greenhouse or like structure. The sill includes a central web portion 55 seated on a portion of the side wall, and is provided with a downwardly extending flange 56 at one end which overlies a portion of the outer face of the side wall; the sill

also includes an upwardly extending flange 57 at the other end of the web 55 the upwardly extending web 57 serving as a shoulder for positioning the hollow sheet metal combination glazing strip and drip gutter.

A modified form of the combination glazing strip and drip gutter tubular sheet metal member is shown in Fig. 3. The combination member differs from the form shown in Figs. 1 and 2, in that the depending leg portion 14 is dispensed with, and a lip or flange 58 is formed at the side of the drip gutter, which is adapted to overlie the upper edge of the upwardly extending flange 67 of the sill in order to hold the combination member in proper position relative to the sill. The lip 58 may be secured in position between a flange 59 of the bracket or post on the upper surface of the sill 53, by a bolt connection 60 or the like. The glass in the vertical side or partition of the greenhouse is designated as 61.

As shown in Fig. 1, the metal roof channel at its end extends downward beyond the sheet metal drip gutter and is shown terminating at a bracket 62 which may be suitably connected to the side of the gutter, or any other suitably fixed support.

One of the important features of this invention is the one which readily adapts a greenhouse or like construction to have additional sections added to the width thereof on either side, without requiring the removal and reconstruction of either of the sides of the greenhouse. For example, Fig. 6 shows diagrammatically one section of a greenhouse, and Fig. 8 is a view showing diagrammatically, a section such as that represented in Fig. 6, after a section has been added to the side of the original section. By embodying the features of this invention, the additional section is added to the side, merely by the construction of the roof and one side, and of course, the ends of the added section, and this is made possible without in any manner tearing down or reconstructing the side of the original section. The gutter, that was originally the end gutter on the first section is now utilized as a middle gutter between the two sections. The outside middle gutter, of course, carries away the water from one-half of each roof section, and the supplemental drip gutter 6 originally installed in the first section, also serves as a means for receiving and conducting the drip water of condensation from the roof bars in one-half of the added section. One very desirable feature is, that the supplemental drip gutter located in the first section can carry away the water of condensation, from one half of the roof bars in the second section. This makes a neat and pleasing appearance in the second section. Of course, the supplemental drip gutter constructed in connection with the additional side of the second section will of course be used.

The novel feature of construction is of particular use, in its application to structure employing a main gutter having a bottom with oppositely sloping portions and being of such contour as to enable the drip water of condensation to follow the outer bottom surfaces of the main gutter concentrating ridge on the bottom thereof and from there drop or be discharged into a supplemental drip gutter supported below.

As shown in Figure 1, the top glazing facia or member 63 is so arranged and disposed as to leave a space 72 between the upper surface thereof, and the bottom of the gutter 1. In order to properly position the upper frame member 63

of the side of the structure, relative to the gutter, suitable angle brackets 66 may be employed, one leg of the bracket being connected with the upper frame member 63 by a bolt 67 or other suitable means, the other leg 66' of the bracket being secured to the gutter in any suitable manner, such as by bolts or the like as shown in Fig. 7. Figure 10 shows more clearly a fragmentary view illustrating the space 72 between the bottom of the main gutter 2, and the upper frame member 63 and also clearly shows the securing bracket 66', which at certain points, is located between the gutter and the frame member 63.

The space 72 between the upper frame 63 and the gutter bottom, is closed and sealed from the outer atmosphere, by means of a sealing or closing strip 64 which extends longitudinally of the gutter and the upper frame member 63. The sealing strip is detachably secured in position in any suitable manner by employing preferably a bolt connection 65 between the strip 64 and the side of the gutter, and preferably a screw or nail connection 65 between the strip 64 and the upper frame member 63. Where an additional section is added at the side, the closing or sealing strip 64 is removed, and if desired the strip may be utilized on the outer side of the added section and thus effect an economy in construction.

As shown in Figure 1, the inner face of the closing strip 64 is provided at its top with a shoulder 70 which rests upon the upper edge of the gutter side, the vertical face 71 of the closing strip preferably being in contact with the outer face of the gutter side. The inner face of the closing strip is also provided preferably with a recess or cut-away portion 69 in order to accommodate the projecting dispersing ridge 68 formed on the gutter.

Figure 7 is an enlarged section showing the above feature of the invention, applied to a greenhouse having a construction including a main gutter, supplemental drip gutter, and framing for the roof bar ends, similar to that shown and described in United States Patent #1,696,160, dated December 18, 1928, in which I was the inventor.

Figure 9 is an enlarged section on the line 9-9 of Figure 8 showing more clearly the relative arrangement of parts adjacent the middle gutter, after the addition has been made at the side of the original section. In view of the full description given in the patent above referred to, it is not thought necessary to give at this time a detailed description of the framing and form of the roof bar ends relative to the gutter sides. It will be sufficient at this time to state that the ends of the wooden roof bars 73 are supported by clasps or brackets 74 which are secured to the side of the gutter 1. The water of condensation from the drip groove 28 in the roof bars 27 is conveyed to the side of the gutter, is dispersed and broken up by the dispersing ridges 68 at the side of the gutter, following the outer surface of the main gutter to the bottom concentrating ridge 4 from which point the water is directed to the supplementary drip gutter 6 below the main gutter. It is to be noted that the drip water of condensation from the roof bars in the added section is conveyed to the side of the gutter of the first section, and passes through the

space 72 between the top frame member 63 and the bottom 2 of the gutter and then is discharged into the supplemental drip gutter in the section. Sufficient space, of course, should be left between the top frame member 63 and bottom of the gut- 145
150

ter, in order to permit the drip water to freely follow the outer under side of the main gutter, without the liability of the path of the drip water being intercepted by the frame member 63.

5. Where the detachable sealing strip is employed in combination with a main gutter having a V shaped bottom or the like, a supplementary drip gutter therebelow and with top frame members of the greenhouse side in spaced relation to the 10 gutter bottom, a considerable economy in time and material is effected where it is desired to add an additional section to the width of the original section.

What I therefore claim and desire to secure by 15 Letters Patent is:

1. In greenhouse construction a combined main gutter, drip gutter and glass stop, comprising a main gutter having upstanding sides having a shoulder on the inner side of the upper edge, a 20 hollow sheet metal member within the greenhouse comprising a combined glass stop and drip gutter for receiving water of condensation directly from the glass and also from the roof bars mounted on the upper edge of the gutter side, said 25 glass stop and drip gutter including a depending portion seated on the shoulder of the upper edge of the gutter, the main body of the hollow sheet metal member including a rectangular body portion arranged normal to the depending portion and mounted upon the upper edge of the 30 gutter side, and extending laterally beyond the sides of the gutter, said sheet metal member having on the top thereof and extending longitudinally thereof, a ridge spaced from the edge and forming a glass stop and one side of a drip or 35 condensation gutter, and a second longitudinally extending ridge spaced from the first ridge and forming the other side of the drip gutter, and means for conveying the drip water from the drip gutter to the main gutter including drain 40 apertures leading to the interior of the hollow member and a drain aperture in the depending portion to discharge the drip water in the main gutter.

45. 2. In greenhouse construction, the combination of a main gutter having an upstanding side, and a hollow member within the greenhouse comprising a combination glass stop and supplemental drip gutter, mounted on the upper edge of said main gutter for receiving water of condensation directly from the glass and also from the roof bars, said combination member including a tubular portion having on its upper face a plurality of spaced upstanding portions one forming the glass stop and one side of the drip gutter, drain apertures in the bottom of the drip gutter, and other drain apertures in one side of the tubular member for conveying the drip water directly to the 55 main gutter.

60. 3. In greenhouse construction including a combination gutter having an upstanding side, a hollow sheet metal combination member within the greenhouse serving as a drip gutter and glass stop mounted on the upper edge of the gutter for receiving water of condensation directly from the glass and also from the roof bars, a plurality of ridges spaced on the upper side of the said member, one of said ridges being arranged intermediate to the sides so as to form a glass stop and one side of drip gutter respectively, drain apertures in the drip gutter to carry the water into the hollow member, and drain apertures in the side of the member to convey the water to the main gutter.

4. In greenhouse construction including in combination a gutter having an upstanding side, a hollow sheet metal combination member within the greenhouse mounted on the upper edge of the gutter side, said member being constructed to serve as a glass stop and a drip gutter for receiving water of condensation directly from the glass and also from the roof bars, said combination member being generally rectangular in form and having on its upper face thereof, a plurality of ridges one of which extends longitudinally of the combination member and is spaced between the sides thereof, and functions as a glass stop on one side of a drip gutter, the other ridge being arranged at the edge of the combination member, drain apertures in the bottom of the drip groove to carry the water of condensation within the hollow member and drain apertures in the side of the hollow member to permit the water of condensation to drain directly into the main gutter, the relative arrangement of the apertures in the bottom of the drip gutter and the aperture in the vertical side of the hollow member being such that a straight implement may be passed therethrough in order to clear the apertures in the event that they become clogged with dirt or the like.

5. In greenhouse construction including in combination a gutter having an upstanding side, having a shouldered portion on the upper edge thereof, a combination drip gutter for receiving water of condensation directly from the glass and also from the roof bars and glass stop comprising a tubular sheet metal member generally rectangular in section within the greenhouse and having a depending hollow portion at the bottom, a drain opening in said depending hollow portion to carry water to the main gutter, a plurality of longitudinally extending ridges on the upper side of said tubular member arranged to form a drip gutter and a glass stop, and a drain aperture in the drip gutter to carry the drip water within the tubular member to the aperture in the depending portion.

6. In greenhouse construction including in combination a gutter having an upstanding side, a wooden roof bar having a drip groove therein, said roof bar also having a seat for receiving glass, a combination drip gutter for receiving water of condensation directly from the glass and also from the roof bars and glass stop comprising a tubular sheet metal member mounted on the upper edge of the gutter, said combination member being generally rectangular in section within the greenhouse and having on the upper face thereof a plurality of ridges one of which is arranged in between the side of the tubular member and serves as a glass stop on one side of the drip gutter, and a second longitudinally extending strip arranged at the outer side of the tubular member and forming the other side of the drip gutter, the end of the wooden roof bars terminating at the drip gutter and having the drip grooves in the roof bar so disposed as to empty the water of condensation directly into the drip groove whereby said drip gutter on account of the tubular member receives the water of condensation directly from the glass and from the drip groove in the roof bars, drain apertures in the drip gutter to carry the drip water within the tubular member and other drain apertures in the upstanding sides of the tubular member in order to carry the water of condensation from within the hollow member directly to the main gutter.

STEPHEN H. HART.
